(57) **CLAIM**

The ornamental design for an eyewear strap as shown and described.

DESCRIPTION

FIG. 1 is a top, front, side perspective view of an eyewear strap showing the new design;

FIG. 2 is a top, rear, side perspective view thereof;

FIG. 3 is a bottom, front, side perspective view thereof;

FIG. 4 is a bottom, rear, side perspective view thereof;

FIG. 5 is a front view thereof;

FIG. 6 is a rear view thereof;

FIG. 7 is a side view thereof;

FIG. 8 is a side view thereof;

FIG. 9 is a top view thereof; and,

FIG. 10 is a bottom view thereof.

The dashed lines shown in the drawings illustrate portions of the eyewear strap and environment that form no part of the claimed design. The dash-dot lines represent boundaries of the claimed design and form no part of thereof.
